UNITED STATES PATENT OFFICE.

EDWARD RUE, OF MINNEAPOLIS, MINNESOTA, ASSIGNOR TO RUE-NELSON MANUFACTURING COMPANY, OF MINNEAPOLIS, MINNESOTA, A CORPORATION OF MINNESOTA.

WASHING MACHINE.

Application filed October 10, 1921. Serial No. 506,686.

To all whom it may concern:

Be it known that I, EDWARD RUE, a citizen of the United States, residing at Minneapolis, in the county of Hennepin and State 5 of Minnesota, have invented certain new and useful Improvements in Washing Machines; and I do hereby declare the following to be a full, clear, and exact description of the invention, such as will enable others skilled in 10 the art to which it appertains to make and use the same.

This invention relates to a washing machine, and particularly to that type of such a machine in which the clothes are placed in 15 a closed receptacle with the washing liquid and are acted upon by reciprocating pounders or pressers.

It is an object of this invention to improve the driving mechanism for the pounders or 20 pressers and to so arrange the same that the operation of said pounders will be discontinued when the cover of the said receptacle is lifted.

It is another object of the invention to 25 provide the machine with a simple and efficient frame of pleasing appearance and to construct the liquid and clothes containing receptacle so that the same is quickly removable bodily from said frame.

It is still a further object of the invention 30 to construct the receptacle with inwardly inclined end walls having an unobstructed bottom wall therebetween and to have the reciprocating and oscillating pounders moving in proximity to the said inclined walls so that the clothes are alternately moved 35 downwardly along said walls, and intermittently moved through the washing fluid in a rotary path.

Another object of the invention is to provide the washing machine with a wringer 40 swingingly mounted at one end of the frame and to provide an improved form of driving mechanism for driving said wringer in either direction.

These and other objects and advantages of the invention will be apparent from the following description made in connection with the accompanying drawings in which like 45 reference characters refer to the same parts throughout the different views, and in which

Fig. 1 is a longitudinal vertical section through the machine the wringer being

shown in side elevation, and the lid of the receptacle, together with the pounders 55 shown moved to open position;

Fig. 2 is a horizontal section taken on the line 2—2 of Fig. 1, as indicated by the arrows;

Fig. 3 is a vertical section taken on the 60 line 3—3 of Fig. 1, as indicated by the arrows and being shown on an enlarged scale;

Fig. 4 is a view in side elevation on an 65 enlarged scale of a portion of the operating mechanism;

Fig. 5 is a top plan view of the machine;

Fig. 6 is a vertical section taken through the driving mechanism for the wringer; and

Fig. 7 is a view on an enlarged scale showing the construction of the receptacle. 70

Referring to the drawings, the machine comprises a rectangular frame having vertical channel members 1 at the corners thereof, the bottoms of which are provided with suitable casters. A sheet metal floor 2 is supported by the members 1 a short distance 75 above the casters and sheet metal side and end members 3 and 4 extend down the sides of the frame from the top to said floor, a door 5 being formed at one end to give access 80 to the parts supported on said floor. The top of the frame is provided with an inwardly extending flange 6 having a rectangular opening at its inner side and a liquid and clothes containing receptacle 7 of rectangular form at its upper portion is disposed in said opening and is provided with outwardly extending angle members 7^a at its upper edge which extend over the flanges 6 85 so that the receptacle 7 is supported by said flanges and is bodily removable upwardly 90 through the opening therebetween.

The washing liquid and the clothes to be washed are placed in the receptacle 7 and the clothes are acted upon by a pair of conical pounder members or cups 8 having their lower open ends of cylindrical shape and formed with suitable smooth flanges or beads. The members 8 are rigidly secured to a curved bar 9, which bar has a hub 9^a 95 formed at its top central portion from which extends upwardly an arm 9^b having a bifurcated upper end. The receptacle 7 is provided with a top hinged cover 10 suitably reinforced by angles at the edge thereof 100 and a plate 11 is secured across the top cen-

tral portion of this cover and has an opening 11^a formed at its central portion with bearing lugs at each side thereof which receive the ends of the pivot member passing through the hub 9^a. The members 8 and 9 are, therefore, pivoted to said plate 11 for oscillating movement. It will be noted that the end walls of the receptacle 7 are inwardly inclined and that the members 8 move downwardly in close proximity thereto. The bottom of the receptacle 7 extending between these inclined portions is entirely unobstructed.

For oscillating the members 8 and 9, the bifurcated end of the arms 9 is connected to a link 12 which extends diagonally across the top of the cover 10 to a point over the flange 6 of the frame and is provided with a forked end extending parallel to the side of said flange. The flange 6 is provided with a slot 6^a and the upper end of a lever 13 extends upwardly through said slot and is pivotally connected to the forked end of link 12. The ends of the link 12 extend some distance beyond the pivotal connection of lever 13 and are formed with curved surfaces 12^a, as shown in Fig. 4, for a purpose to be later described. The lever 13 for the intermediate portion of its length is formed of spaced members 13^a and these members extend downwardly on each side of a bracket member 14 secured to the side and end walls 3 and 4 of the machine frame. The member 14 is formed with a slot 14^a in its upper side in which normally seats a pivot member 13^b secured in and extending between the members 13^a. The lower end of the lever 13 is pivotally connected to a pitman 15 which is, in turn, pivoted at its other end to an eccentric strap surrounding an eccentric 16 carried by a vertically extending shaft 17. The latter shaft extends vertically from a worm wheel 18 to which it is rigidly secured, which worm wheel meshes and is driven by a worm gear 19, the worm wheel and gear being enclosed in a suitable housing 20. The worm gear 19 has a shaft secured thereto and extending from the housing 20 which is driven by a pulley 21 secured thereto which is, in turn, driven from the usual electric motor 22, through a belt 23, the motor and housing 20 being suitably supported on the floor 2 of the machine frame.

A wringer, designated generally as *a*, is mounted in a post 24 secured to the top of the frame, the wringer being rotatable in said post and held in various rotated positions by a pivot catch 24^a adapted to engage in spaced slots in the flange on the top of said post. In order to drive the rollers of the wringer, the same are connected by suitable gears to a beveled gear 25 with which mesh reversely disposed beveled pinions 26 and 26^a. A shaft 27 extends through said pinions and projects downwardly into

the post 24, said shaft having its lower end angularly formed and extending into an angularly formed socket in the upper end of a rotatable member 28. The latter member extends downwardly through the post 24 and is connected by a universal joint to a connecting rod 29 which is, in turn, connected at its other end by a universal joint to the top of the shaft 17. When the motor 22 is running the gears 25, 26 and 26^a will therefore be turned. The pinions 26 and 26^a are formed with grooves in their adjacent faces and the shaft 27 is provided with cross pins 27^a adapted to be received in said grooves. The upper end of the shaft 27 has a collar thereon which, together with the end of said shaft, is received in a head member 30. A bail 31 is connected to the sides of said head and extends over the same and an eccentric member 32 having an eccentric hub portion, is received between the top of the head 30 and the underside of the bail 31. The eccentric 32 is pivoted to the side of a frame member 33 of the wringer and is provided with an operating handle so that when swung to one side or the other, the shaft 27 will be raised or lowered and the pins 27^a moved into engagement with either one of the pinions 26 or 26^a, thus connecting the said pinion and the gear 25 to said shaft. The wringer can thus be driven in either direction depending upon which pinion is engaged. As shown in Fig. 6, the shaft 27 can be held in position with both pinions disengaged and when in this position, the wringer will not be operated. A plate 34 is provided having suitable means thereon to hold the handle of the eccentric in its adjusted position.

In operation, the clothes will be placed in the receptacle 7 and when the motor is started, the lever 13 will be oscillated about its fulcrum 13^b and the members 8 and 9 will thus be oscillated, the members 8 pressing down on the clothes and forcing the water therethrough. When the members 8 rise, a suction will be exerted on the clothes and the water will thus be drawn through the same. A thorough cleansing and bleaching action is thus secured.

The present machine is an improvement over the machines disclosed in applicant's prior Patents 773,101, granted October 25th, 1904, and 824,674, granted June 26th, 1906. In said patents, member 3 was disposed in the bottom of the receptacle between the members 8 to prevent the clothing from being moved laterally. The advantages of a protuberance in the bottom of hand-operated washing machines, of the type disclosed in my former patents, when the oscillating stroke of the pounders is variable, is obvious. It has been found impractical, however, to similarly construct a power-operated machine where the stroke of the pound-

ers must necessarily be fixed. It will be readily seen that such a protuberance, or other obstruction to the free circulation of the clothes in the receptacle, through the 5 washing fluid, during the positive operation of the pounders, would cause the machine to stall or otherwise interfere with the desired operation thereof. It has also been found desirable to incline the end 10 walls of the receptacle at an angle of approximately 45° to the bottom, so that the pounders will travel in close proximity thereto during their operation upon the clothes. The clothes then fall outward toward 15 the end of the receptacle and are again pressed downwardly by the members 8. The clothes are thus rotated or turned over by the action of the members 8 in connection with the inclined ends and the unobstructed bottom. This results in all parts 20 of the clothes being brought under the action of the members 8 and thus efficiently washed.

When the cover 10 is lifted, as indicated 25 in dotted lines in Fig. 1, the extended ends 12^a of the link 12 bear upon the top of the flange 6 at the sides of the slot 6^a and lift the lever 13. The fulcrum pin 13^b is thus 30 lifted out of the slot up to member 14, as shown in dotted lines in Fig. 1. The lever then merely swings about its pivotal connection with the lever 12 and no motion is transmitted to the link 12 or member 9. The lifting of the cover, therefore, disconnects 35 the driving mechanism from the members 8 or 9 or renders the same inoperative.

The operation of the wringer has been sufficiently described and it is thought the same needs no further explanation. It will 40 also be noted that the receptacle 7, together with the lever 12 and parts 8 and 9, can be bodily lifted from the frame by disconnecting the link 12 from the lever 13.

From the above description it is seen that 45 applicant has provided an improved and efficient structure of washing machine, the parts of which are simple, easily constructed and arranged to be of easy access for any necessary attention.

50 It will, of course, be understood that various changes may be made in the form, details and arrangement of the parts without departing from the scope of applicant's invention, which, generally stated, consists in the matter shown and described and set forth in the appended claims.

What is claimed is:

1. A washing machine having in combination, a frame, a liquid and clothes receptacle 55 supported therein, a hinged cover for said receptacle oscillatory means in said receptacle for acting on the clothes, means for actuating said oscillatory means including a lever fulcrumed on a horizontal pivot, and also including means for lifting

said lever from its fulcrum when the cover is raised to thereby stop the actuation of said oscillatory means.

2. A washing machine having in combination, 70 a frame, a receptacle therein adapted to receive the clothes and washing liquid movable means therefor for operating on the clothes, a driving mechanism for said means comprising a pair of levers and a link connecting said levers to said movable means 75 and a hinged cover for said receptacle, said link having an extension at one end forming a lifting cam arranged, when said cover is raised, to engage the frame and lift one of said levers to render the same and said driving mechanism inoperative.

3. A washing machine having in combination, 80 a frame, a receptacle mounted therein adapted to receive the clothes and washing liquid, a swinging cover for said receptacle oscillatory means therein for acting on the clothes, a bracket secured to the frame having a slot therein, a lever having a pivot seated in the slot in said bracket forming part of an actuating means for 85 said oscillating means, and means connected to said lever and cover whereby when said cover is raised, the lever will be lifted and its pivot removed from said slot whereby the oscillating means will cease 90 to be driven.

4. A washing machine having in combination, 95 a frame, a receptacle mounted therein adapted to receive the clothes and washing liquid, an oscillating member 100 therein for acting on the clothes, a link connected to said oscillating member having one end disposed over said frame, a vertically extending lever pivotally connected at its upper end to said link, said 105 lever being pivoted in a bracket secured to said frame, the end of said link being projected beyond the pivotal connection with said lever to form a cam means, a hinged cover for said receptacle on which said oscillating means is mounted, whereby when the said cover is raised, the extended end of said link will act as a cam on said frame and raise the lever to lift the pivot thereof 110 from said bracket.

5. A washing machine having in combination, 115 a frame, a receptacle supported therein adapted to receive the clothes and washing liquid and having end walls inclined at an angle of approximately 45° degrees, oscillating spaced pounders oscillating in a vertical plane in close proximity to said walls and acting alternately to push the clothes downwardly along the same, said receptacle having an unobstructed flat 120 bottom between said pounders whereby the clothes will be given a rotary motion downwardly along said walls and upwardly between said pounders.

6. A washing machine having in combi- 125

nation, a frame, a rectangular receptacle supported therein adapted to receive the clothes and washing liquid and having a plane bottom and inwardly inclined end walls disposed at an angle of approximately 45 degrees, and means mounted in said receptacle for alternately pushing the clothes downwardly and inwardly along said end walls, the space between said walls being unobstructed whereby the clothes will be intermittently moved and a rotary motion imparted thereto.

7. A power-operated washing machine comprising in combination with a supporting frame, a motor, and a receptacle for the clothes and washing fluid carried by said frame, said receptacle having a substantially flat unobstructed bottom portion and end walls inclined at an angle of approximately 45° to said bottom, clothes pounders pivotally mounted within said receptacle on a horizontal axis and adapted

to oscillate through a predetermined cycle during the operation of the machine, and means operatively connecting said pounders and motor whereby the pounders are caused to operate alternately upon the clothes in the receptacle and whereby to cause a circulation of the clothes in a rotary path through the washing fluid, substantially as described.

8. A washing machine comprising a receptacle adapted to contain the liquid and clothes, said receptacle having inwardly inclined end walls and spaced alternately operating oscillating means adapted to move downwardly adjacent said walls, the angle of said walls being such that said means co-operates with said walls to revolve said clothes.

In testimony whereof I affix my signature.

EDWARD RUE.
